UNITED STATES PATENT OFFICE.

GRANT HOLMES, OF DANVILLE, ILLINOIS, ASSIGNOR TO THE MARION STEAM SHOVEL COMPANY, OF MARION, OHIO, A CORPORATION OF OHIO.

TRUCK.

Application filed August 6, 1923. Serial No. 655,880

This invention relates to trucks and more particularly to trucks for self propelled machines, such as excavating machines, which are advanced from one position to another 5 as the work progresses.

The invention is designed primarily for use with large excavating machines, such as rotary steam shovels, which are used for stripping the over-burden from surface deposits of coal, ore and the like. These machines are of very large size and great weight and they are usually supported by four separate trucks, one arranged at each corner of the machine. Each of these trucks comprises 10 four track wheels which travel over tracks formed of sections of railroad rails which may be mounted either on ties or directly on the surface of the coal from which the over-burden has been removed. These rails are necessarily in comparatively short sections 15 so that they can be readily disconnected and the rear sections moved to the front as the machine advances. The rail sections are connected one to the other by fish plates in the usual manner but the joints between the rail sections constitute weak points in the track, particularly if the joint happens to be located above a soft spot in the ground or coal, which are likely to yield under the immense 20 weight to which they are subjected, thus forcing the joint downwardly, elevating the other ends of the rails and permitting the truck and that portion of the machine supported thereby, to sag or follow the depressed joint downwardly. This not only imposes a 25 strain upon the machine which is very detrimental thereto but, even in the absence of injury to the machine itself, it causes serious delays, and the elevation of the machine, the rebuilding of the track and the remounting of the trucks on the tracks involves a great deal of labor and expense. Even though the 30 yielding of a joint may not be sufficient to injure the machine or wreck the track it is very likely to derail the truck. Further, the tracks are formed of standard railroad rails having a relatively narrow base and these rails have a tendency to tilt under the strains to which 35 they are subjected, especially when they are mounted upon the surface of the coal itself.

In order to overcome these difficulties it is one object of the invention to provide a truck in which the track sections will be without joints and will be advanced from time to time 40 relatively to the truck wheels to provide at

all times a track surface in front of the wheels over which they may travel.

A further object of the invention is to provide means whereby the track members or sections may be relieved of their load to permit of their being advanced beneath the 60 wheels and relatively thereto.

A further object of the invention is to provide a truck of this character in which the weight of the machine may be utilized for advancing the track members.

A further object of the invention is to provide a truck of this character which will be comparatively simple in its construction and operation and which will be of a strong durable character; and in which the track members will have wide base portions which will prevent them from tilting.

Other objects of the invention will appear as the device is described in detail.

In the accompanying drawings Fig. 1 is a side elevation of a portion of an excavating machine showing my invention applied thereto; Fig. 2 is an end elevation of such a machine; Fig. 3 is an end elevation of one of the trucks, partly broken away; Fig. 4 is a plan view of one of the trucks; Fig. 5 is a side elevation of a truck, partly broken away; Fig. 6 is a longitudinal section taken on the line 6—6 of Fig. 4; Fig. 7 is a section taken 70 on the line 7—7 of Fig. 4; and Fig. 8 is a section taken on the line 8—8 of Fig. 4, partly broken away.

In these drawings I have illustrated one embodiment of my invention and have shown the same as applied to a rotary stripping shovel but it will be understood that the invention may be applied to excavating machines or other machines of various kinds and that the mechanism may take various 85 forms without departing from the spirit of the invention.

In carrying out my invention I provide a plurality of track members which are mounted for longitudinal movement over the 90 ground or other supporting surface. These track members are arranged below the truck frame and the wheels on the truck frame are adapted to travel over the respective track members, thus supporting the load on the 95 several track members. These track members being without joints throughout their length provide a very rigid and unyielding support for the machine. The length of the track members is such that the truck wheels may 100

have a limited traveling movement thereon but as the wheels approach the limit of their movement on the track members the latter will advance relatively to the truck wheels 5 and without otherwise displacing the same with relation thereto, so as to provide an additional track surface in front of the truck wheels. In order that the track members may be readily advanced means are provided 10 for relieving the same of the weight of the load during the time of their forward movement. In order that the load may be adequately supported I prefer to arrange the track members in pairs and to alternately 15 relieve the track members of each pair of their load and to advance the same while thus relieved of the load. These results may be accomplished in various ways and the particular mechanism hereinafter described has been 20 chosen for the purpose of illustration only.

As shown in these drawings the stripping machine comprises a base or main frame portion 1 which is preferably rectangular in shape and on which is mounted a rotating 25 platform 2 which carries the power plant and operating mechanism and on which is mounted a boom 3 carrying the excavating dipper and its associated mechanism. The machine itself is of a well known construction 30 and need not be here described in detail. Beneath each of the four corners of the base or main frame 1 of the machine is mounted a separate truck which carries the weight of the adjacent portion of the machine. The 35 several trucks are similar in construction and it will be necessary to describe but one of them.

In that particular embodiment of the invention which I have here illustrated each 40 truck comprises a main frame or body portion 4 having journaled therein two axles 5 and 6 on each of which are mounted four track wheels 7, 8, 9 and 10, which are here shown as double flanged wheels. Means are 45 provided for positively driving these truck wheels for the purpose of advancing the machine when it is desired to move it from one position to another and preferably this is accomplished by connecting with the respective axles, 5 and 6, gears 11 and 12, which gears, in the present instance, are rigidly secured to the inner wheels 7 on each axle. Meshing with both gear wheels is a pinion 55 13 which, in the present instance, is rotatably mounted on a stud 14 rigidly secured to the main truck frame 4. This pinion is connected by means of a universal joint 15 to a transverse shaft 16 which is connected at its inner end by a second universal joint 17 with a short 60 shaft 18, which in turn is connected by beveled gears 19 with a longitudinally extending driving shaft 20 having at its inner end a beveled gear 21 by means of which it may be driven through a vertical shaft arranged at 65 the axis of rotation of the platform 2 and

driven from an engine on that platform, in a well known manner. Arranged beneath the truck frame are a plurality of track members 22, 23, 24 and 25, upon which the wheels 7, 8, 9 and 10, respectively, travel. These 70 track members are separate one from the other and are individually capable of longitudinal movement relatively one to the other and relatively to the truck wheels. The tracks may be of any suitable character but, 75 as here shown, each track member comprises a relatively wide base portion 26 having an upwardly extending longitudinal rib 27 which constitutes the rail on which the wheels travel. Each track member is without joints 80 and to this end it is preferably formed in a single piece and is of such length that the wheels may have a limited traveling movement thereon. Inasmuch as the track members are designed for sliding movement over 85 the ground, or other supporting surface, I have shown the end portions thereof as beveled or turned upwardly at 28, after the manner of sled runners.

In order that each track member may be 90 easily advanced relatively to the truck wheels it is desirable that it should, during its advancing movement, be relieved from the weight of the load. To accomplish this I have, in the present form of the truck, provided the tread portion of each of the truck wheels with a plurality of flattened surfaces, 95 as shown at 29. These flattened surfaces are spaced apart equal distances about the periphery of the tread and are separated by the 100 normally rounded tread portions, which rounded portions are preferably of greater length than the flattened portions. To provide means for supporting the weight of the load during the advancement of the tracks 105 the flattened portions on adjacent wheels are arranged out of line one with the other so that when one wheel is out of supporting contact with its track member the adjacent wheel will be in supporting contact with its track 110 member. In the present arrangement of the truck the track members are arranged in pairs, one pair, consisting of the track members 22 and 23, being arranged on one side of the longitudinal center of the truck and the 115 other pair, consisting of the track members 24 and 25, being arranged on the other side of the center of the truck. In the present arrangement the outer truck wheels 7 and 10 have their flattened portions arranged in line one 120 with the other and the inner wheels 8 and 9 have their flattened portions arranged in line one with the other but out of line with the flattened portions of the wheels 7 and 10. The rounded portions of the tread of each 125 wheel being greater than the flattened portions thereof, it will be apparent that as the wheels advance over the track members the flattened portions of the wheels 7 and 10, for example, will lie adjacent to the respective 130

- tracks and these tracks will be free from the load, at the same time the rounded portions of the treads of the wheels 8 and 9 will be in engagement with their respective track members and the load will be supported on the track members 23 and 24. As the wheels travel over the track members the rounded portions of the treads of the wheels 7 and 10 will engage the respective track members 5 some little time before the rounded portions of the treads of the wheels 8 and 9 move out of engagement with the track members 23 and 24. Consequently at fixed intervals during the travel of the truck wheels over the track 10 all four of the wheels on each axle will be in supporting contact with their respective track members and as the wheels continue to advance the two track members of each pair will be alternately relieved from the load so that 15 they are free to be advanced. It will be obvious that the "flattened" portions of the wheels need not be strictly flat but that it will be sufficient if the radii of these portions are shortened so that they will be supported 20 out of contact with the track members. It will also be apparent that either wheel on one pair of track members may have its flattened portions in line with the flattened portions of either wheel on the other pair of track members. 25
- Longitudinal movement may be imparted to the respective track members in any suitable manner but I prefer, when practical, to utilize the weight of the machine itself for 30 imparting this movement to the track members and, in the present construction, I have provided fluid operated devices for actuating the track members. As here shown, I have provided adjacent to each pair of track members, 22 and 23, and 24 and 25, a forwardly extending fluid cylinder 30 in which is mounted a piston 31 having a piston rod 32 extending beyond the open forward end of the cylinder. This piston rod is operatively connected 35 with the two track members of that pair of track members with which the cylinder is associated. In the present instance, the outer end of the piston rod 32 is pivotally connected with a floating lever 33 the upper end of 40 which is connected by a link 34 with the frame 4 of the truck. The lower end of the lever beneath its point of connection with the piston rod is connected with a connecting rod 35 which extends rearwardly to a point near the 45 rear end of the truck where it is pivotally connected with an equalizing bar or lever 36, the point of connection being preferably midway between the ends of that bar. The bar 36 is connected at each end with the rear ends of 50 the respective track members and, as here shown, each end of the equalizing bar is provided with a longitudinal slot 37 through which extends a pin 38 mounted in the end of the track member. Preferably the track members are provided with transverse slots 55
- 39 through which the ends of the equalizing bar loosely extend and the pins 38 are seated in the track member both above and below the slots 39, so as to provide a very strong connection. It will be apparent that when 60 the piston 31 is subjected to fluid pressure the lever 33 through the connecting rod 35, will exert pressure on the equalizing bar 36. When one of the track members is relieved of its load this pressure on the equalizing bar 65 will cause that track member to slide forward beneath the truck wheels, the flanges on the truck wheels serving as guides to prevent the lateral displacement of the track member. If desired, each pair of track members may 70 be provided with a second operating cylinder 40 having a piston 41 and piston rod 42 which may be connected with the forward ends of the track members in order to move the same 75 rearwardly when it is desired to reverse the direction of the movement of the machine. In the present instance, I have shown no connecting mechanism between the piston rod 42 and the forward ends of the track members, it being the intention to disconnect the lever 80 85 90 95 100 105 110 115 120 125 130
- 33, the connecting rod 35 and equalizing bar 36 and reverse the same so that the equalizing bar will be connected with the forward ends of the track members and the lever will be connected with the rearwardly extending piston rod 42. Obviously, however, the connecting devices may be duplicated, if desired, and one or the other of the operating mechanisms may be disconnected from the tracks when the other operating mechanism is in use. Fluid under pressure may be supplied to the operating cylinders 30 and 40 in any suitable manner but, as has been stated, I prefer to utilize the weight of the machine for actuating the track members and I have therefore provided the main truck frame 4 with a vertical cylinder 43 adapted to contain a suitable fluid and connected at its lower end, by means of conduits 44, with the several operating cylinders 30 and 40. Suitable means are provided for controlling the connection between the cylinder 43 and the several operating cylinders and, in the present instance, I have provided individual valves 45 and 46 for controlling the several conduits, the valves 45 controlling the connection between the conduits and the forwardly extending cylinders 30 and the valves 46 controlling the conduits for the rearwardly extending cylinders 40. Mounted in the vertical cylinder 43, and supported by the fluid therein, is a piston 47 the upper end of which projects above the top of the cylinder and constitutes a support on which the corner of the base 1 rests, thus causing the piston to be subjected to the entire weight of the adjacent portion of the machine, the whole weight of the machine being divided between the pistons 47 of the four trucks. This great weight imposed upon the piston 47 subjects the fluid in the cylinder 130

43 to a very high pressure and when one of the controlling valves, the valve 45 for example, is opened, this pressure will be transmitted to the piston 31 in the operating cylinder 30. It will be understood that the valves 45 for the two forwardly operating cylinders are opened when it is desired to advance the machine, the valves for the rearwardly operating cylinders remaining closed. 5 When it is desired to reverse the direction of the machine the valves 45 will be opened and the valves 45 will remain closed. When the valves 45 have been opened so that the pistons 31 are subjected to the 10 pressure created by the weight of the load, power is applied to the truck wheels to advance the same along the track members. As soon as the flattened portions of one set of wheels move into positions adjacent to the 15 respective track members, so that these track members are relieved of the weight of the load, the pressure on the piston 31 will actuate the connecting rod 35, thus causing the equalizing bar or lever 36 to fulcrum about its 20 point of connection with that track member which supports the load and causing the opposite end of the equalizing bar or lever to move forwardly, thus pushing the released track member forward beneath the wheels 25 which cooperate therewith. It will be understood, of course, that because of the arrangement of the wheels and the operating mechanism above described the corresponding track members of the two pairs of track members 30 will be operated simultaneously in the same manner. After the released track member has been fully advanced the rounded portions of all of the wheels will engage the track members so that all will be under load and 35 will thus be held against movement relative to the truck wheels. As the wheels move forward on the stationary track members the truck frame will advance the cylinders 30 with relation to their pistons, which pistons 40 are held against movement because of their connection with the track members, and will thus force the fluid out of the cylinders 30 and back into the main vertical cylinder 43. The interval during which all the truck 45 wheels rest upon the track members is sufficient to restore the pistons 31 to their normal positions. When this has been accomplished the flattened portions of the second set of truck wheels are brought into positions 50 adjacent to their respective track members and these track members are released for movement and are advanced in the same manner that the first mentioned track members were advanced. This operation will continue 55 so long as the valves controlling the connections between the vertical cylinder and the operating cylinders remain open and power is applied to the truck wheels to rotate the same. 60

65 The outward movement of the floating

lever 33 is limited by a stop 50 which is here shown in the form of a slotted arm secured to the truck frame 4 and through which the lever extends. This stop serves to limit the forward movement of the piston and of the track member but as the truck frame moves forwardly the piston and track member will be permitted to advance. Any number of flattened portions may be provided on the treads of each wheel but when more than two flat portions are provided the length of the rounded portions of the several wheels which will simultaneously engage their respective track members is comparatively short and may, in some instances, result in a movement of the track members which is objectionably short. This will be due to the fact that both track members are not held against movement long enough to permit the cylinder to be advanced for the full length of the piston stroke. Should this happen means may be provided for locking that track member which has been advanced against further movement until the other track member has been released, thus holding both track members against movement for a length of time sufficient to permit the cylinder to be advanced for substantially the full length of the piston stroke. This may be accomplished in various ways. As here shown, the two track members of each pair are each provided with a pair of lugs, the lugs on the track member 24 being indicated by lugs 51 and 52 and the lugs on the track member 25 being indicated by the lugs 53 and 54. The lugs 51 and 52 are spaced apart a greater distance than are the lugs 53 and 54 and the latter lugs extend between the lugs 51 and 52 and are so arranged with relation thereto that when the track member 24 has been moved to its foremost position the lug 52 on that track member will engage the lug 54 on the track member 25, which is held against movement, and will thereby prevent the further forward movement of the track member 24 as the frame of the truck advances, it being understood that this locking device holds the track member 24 against movement until the wheels resting thereon have rotated far enough to bring the rounded portions of the tread into contact with the track member. The lug 53 in the track member 25 is so arranged with relation to the lug 51 on the track member 24 that it will engage the same when the track member 25 has advanced to the limit of its forward movement with relation to the truck, the operation in this instance being the same as that above described. 105

110 When the desired movement of the machine has been accomplished the rotation of the truck wheels is stopped and the valves may be closed if desired but this is not necessary. The truck wheels are preferably stopped in such positions that all eight of the wheels of 115 120 125 130

the truck will rest upon their respective track members, thus providing an eight point support for the machine upon the wide base track members, which support is very rigid and 5 absolutely unyielding.

In the old type of truck above referred to the constant vibration or hammering on the wheels results in the treads thereof being peened or flattened in spots which in time 10 seriously injures the wheels and is detrimental to the operation and shortens their life. With the truck wheels arranged as shown in the present machine, and particularly when eight truck wheels are used, this 15 peening or hammering of the wheels is very largely eliminated.

While I have shown and described one embodiment of my invention I wish it to be understood that I do not desire to be limited 20 to the details thereof as various modifications may appear to a person skilled in the art.

Having now fully described my invention, what I claim as new and desire to secure by 25 Letters Patent, is:

1. In a truck, a main frame, wheels mounted thereon, a pair of separate track members upon which the respective wheels are adapted to travel, means for actuating said wheels to 30 move the same along said track members, said wheels having means for alternately relieving said track members of the load thereon, a power operated actuating device carried by said truck frame, and a connecting member 35 operatively connected with both track members and with said actuating device and so arranged that the force applied thereto by the actuating device will cause whichever track member is relieved of its load to be 40 advanced with relation to the other track member.

2. In a truck, a main frame, wheels mounted thereon, a pair of separate track members upon which the respective wheels are adapted 45 to travel, means for actuating said wheels to move the same along said track members, said wheels having means for alternately relieving said track members of the load thereon, a power operated actuating device carried by 50 said truck frame, and a lever connected at its ends with the respective track members and connected between its ends with said actuating device, whereby the action of said actuating device on said lever will advance that track member which has been relieved of its load.

3. In a truck, a main frame, wheels mounted thereon, a plurality of separate track members upon which the respective wheels are 55 adapted to travel, means for actuating said wheels to move the same along said track members, said wheels having means for alternately relieving said track members of the load thereon, an actuating device carried by 60 said truck frame, a connecting member op-

eratively connected with both track members and with said actuating device and so arranged that the force applied thereto by said actuating device will advance whichever track member is relieved of its load, and 70 means controlled by the weight of the load on said truck for operating said actuating device.

4. A truck comprising a pair of track members, wheels adapted to travel on the respective track members, each of said wheels having its tread provided with a flattened portion, said flattened portions of the respective wheels being arranged out of line one with the other, a lever connected at its ends 75 with the respective track members, and means for applying power to said lever near the center thereof, whereby when one of said track members is relieved of its load because of the proximity of the flattened portion of its wheel thereto, the thrust on said lever will impart longitudinal movement to said track member.

5. In a truck, a main frame, wheels mounted thereon, a plurality of separate track members on which the respective wheels are adapted to travel, means for actuating said wheels to move the same along said track members, said wheels having means for alternately relieving said track members of the load thereon, a fluid operated device mounted on said truck frame, a lever connected with said track members, means for operatively connecting said lever with said fluid operated device, whereby said fluid operated device will be caused to act upon that track member which 90 has been relieved of its load.

6. In a truck, a pair of parallel track members, a frame arranged above said members, wheels carried by said frame and adapted to travel on said track members, means for rotating said wheels, said wheels having means for alternately relieving said track members from the load, a lever pivotally connected at its ends with the respective track members, a cylinder, a piston mounted in said cylinder, a piston rod connecting said piston with said lever at a point between said track members, and means for supplying fluid under pressure to said cylinder.

7. In a machine of the character described, a truck to support a portion of said machine, said truck comprising wheels, track members over which said wheels travel, and means actuated by the weight of the load on said truck for imparting longitudinal movement to said track members.

8. In a machine of the character described, a truck on which a portion of the weight of said machine is supported, a plurality of track members, wheels adapted to travel on the respective track members, means controlled by said wheels to relieve one of said track members of its load, and means actuated by the weight of the machine on said 125

truck to impart longitudinal movement to the track member which has been so relieved of its load.

9. In a machine of the character described, a truck adapted to support a portion of the weight of said machine and comprising a pair of track members, wheels adapted to travel on the respective track members, means for rotating said wheels to move the same along said track, said wheels being so shaped and arranged with relation one to the other that said track members will be alternately relieved of the load on said truck, and means actuated by the weight of the load on said truck for imparting longitudinal movement to each track member when it is relieved of its load.

10. In a machine of the character described, a truck to support a portion of the weight of said machine and comprising a pair of track members, wheels adapted to travel on said track members, driving mechanism for said wheels, said wheels having portions of their treads flattened, the flattened portions of the treads of the two wheels being so arranged that said track members will be alternately relieved of the weight of the load on said truck, a mechanism for imparting longitudinal movement to the track member which has been so relieved, and means actuated by the weight of the load on said truck for imparting movement to said actuating mechanism.

11. In a machine of the character described, a truck to support a portion of the weight of said machine and comprising a pair of track members, wheels adapted to travel over said track members, driving mechanism for said wheels, said wheels being of such a character and so arranged that said track members will be alternately relieved of the load on said truck, a fluid operated device for imparting longitudinal movement to the respective track members when they are so relieved of their load, and means operated by the weight of the load on said truck for supplying fluid under pressure to said fluid actuated device.

12. In a machine of the character described, a truck comprising a main frame, a vertical fluid cylinder carried by said frame, a piston mounted in said cylinder and arranged to support the load on said truck, wheels mounted on said frame, means for rotating said wheels, separate track members on which the respective wheels travel, said wheels having portions of their treads flattened, the flattened portions of the several wheels being so arranged that said track members will be alternately relieved of the weight of the load on said truck, a fluid operated device for imparting longitudinal movement to the respective track members when they have been relieved of their load, and a

conduit connecting said fluid actuating device with said cylinder.

13. In a machine of the character described, a frame, a cylinder carried by said frame and adapted to contain a fluid, a piston mounted in said cylinder and arranged to support the load on said truck, wheels carried by said frame, separate tracks over which said wheels are adapted to travel, means controlled by the movement of said wheels to alternately relieve said tracks of the load on said truck, and means actuated by the pressure of said piston on the fluid in said cylinder to impart longitudinal movement to that track member which has been relieved of its load.

14. In a machine of the character described, a truck comprising a frame, a pair of track members arranged on each side of the center of said frame, axles journaled in said frame and extending transversely to said track members, wheels mounted on said axles and adapted to travel on the respective track members, means for driving said wheels, said wheels being so shaped and arranged with relation one to the other that as they move over said track members the latter will be alternately relieved of the weight of the load on said truck, a cylinder carried by said frame adjacent to each pair of track members, a piston mounted in each cylinder, an operative connection between each piston and the adjacent pair of track members, a vertical cylinder carried by said frame and adapted to contain a fluid, a piston mounted in said vertical cylinder and adapted to support the load on said truck, and a valve controlled connection between said vertical cylinder and the first mentioned cylinder.

15. In a machine of the character described, a truck comprising a frame, a pair of track members arranged on each side of the center of said frame, axles journaled in said frame and extending transversely to said track members, wheels mounted on said axles and adapted to travel on the respective track members, means for driving said wheels, said wheels being so shaped and arranged with relation one to the other that as they move over said track members the latter will be alternately relieved of the weight of the load on said truck, a cylinder carried by said frame adjacent to each pair of track members, a piston mounted in each cylinder, equalizing levers connected at their ends with the track members of the respective pairs, rods connected with the respective levers between the ends thereof, operative connections between said connecting rods and respective pistons, a vertical cylinder carried by said frame and adapted to contain a fluid, a valve controlled connection between said vertical cylinder and each of the first mentioned cylinders, and a piston mount-

ed in said vertical cylinder and adapted to support the weight of the load on said truck.

16. In a truck, a pair of track members, a frame arranged above said track members, 5 wheels carried by said frame and adapted to travel on said track members, means for rotating said wheels, said wheels having means for alternately relieving said truck members from the load, a cylinder carried by said 10 frame, a piston mounted in said cylinder, a connection between said piston and said track members, and means for supplying fluid under pressure to said cylinder whereby the track member which has been relieved of 15 the load will be advanced, said wheels also having means for holding both track members against movement for an interval between the movements of the respective track members, whereby the movement of said 20 frame will move said cylinder with relation to said piston.

17. In a truck, a frame, wheels mounted thereon, driving means for said wheels, a plurality of separate track members on which 25 the respective wheels are adapted to travel, the tread of each wheel having adjacent flat and rounded portions, the flat portion on one wheel being out of line with the flat portion of another wheel, whereby the respective track 30 members will be alternately relieved of the load on said truck, said flat portions being so arranged that both track members will be held against movement for an interval between the movements of the respective track 35 members, a cylinder carried by said frame, a piston mounted in said cylinder, an operative connection between said piston and said track members, and means for supplying

fluid under pressure to said cylinder to advance the track member which has been relieved, the forward movement of said frame during the interval that both track members are held against movement serving to move 40 said cylinder relatively to the piston to restore the piston to its initial position. 45

18. A truck comprising a pair of track members, wheels adapted to travel on the respective track members, each of said wheels having its tread provided with a flattened portion, said flattened portions of the respective wheels being arranged out of line one with the other, means for imparting longitudinal movement to said track members when the flattened portions of the wheels are adjacent thereto, and locking means for controlling the longitudinal movement of said track members with relation one to the other. 50 55

19. A truck comprising a pair of track members, wheels adapted to travel on the respective track members, each of said wheels 60 having its tread provided with a flattened portion, said flattened portions of the respective wheels being arranged out of line one with the other, and means for imparting longitudinal movement to said track members 65 when the flattened portions of the wheels are adjacent thereto, the track members of each pair having cooperating lugs arranged to lock one of said track members against forward movement with relation to the other when the first mentioned track member has been moved to a predetermined position. 70

In testimony whereof, I affix my signature hereto.

GRANT HOLMES.
